UNITED STATES PATENT OFFICE.

HEADLEY THOMPSON, OF HECTOR, NEW YORK.

IMPROVEMENT IN BRANDS FOR MARKING ANIMALS.

Specification forming part of Letters Patent No. **64,263**, dated April 30, 1867.

To all whom it may concern:

Be it known that I, HEADLEY THOMPSON, of Hector, in the county of Schuyler and State of New York, have invented a new and Improved Stamp for Marking Animals, and other like uses; and I do hereby declare that the following is a full, clear, and exact description of the same, reference being had to the annexed drawings, making part of this specification, in which—

Figure 1 is a plan, Fig. 2 is a side elevation, and Fig. 3 is a perspective view, of one of the sockets.

The same letters are employed in all the figures in the designation of the same parts.

A A A are movable letters of metal, which may be used for stamping or branding. They are constructed with stems A' projecting from the back at the center of the letter, or in such manner that the point of support may permit the adjustment of the letter in proper relation to the other letters with which it may be used.

B is the stock constructed with two, three, or more prongs which terminate with a socket, B', to receive the stem A' of the letter. When the stem is inserted in the socket it is held in place by the thumb-screw C passing through the shell of the socket and pressing against the side of the stem.

What I claim as my invention, and desire to secure by Letters Patent as an article of manufacture, is—

The movable type A constructed with stem A' thereto attached, in combination with the stock B constructed with sockets B' and the thumb-screws C, and arranged for use substantially as and for the purpose set forth.

In testimony whereof I have signed my name to this specification in the presence of two subscribing witnesses.

HEADLEY THOMPSON.
